UNITED STATES PATENT OFFICE.

CHARLES F. CUNO, OF MERIDEN, CONNECTICUT.

ELECTRIC CIGAR-LIGHTER.

1,346,368.

Specification of Letters Patent.

Patented July 13, 1920.

Application filed March 8, 1920. Serial No. 364,260.

To all whom it may concern:

Be it known that I, CHARLES F. CUNO, a citizen of the United States of America, residing at Meriden, New Haven county, 5 Connecticut, have invented a new and useful Electric Cigar-Lighter, of which the following is a specification.

My invention relates particularly to a device intended to be used on automobiles. 10 Here great difficulty is frequently found in lighting a cigar by the ordinary electrical devices on account of the wind which frequently tends to so cool off the device as to make it inoperative. With the ordinary 15 device the igniting element is so exposed that there is danger of setting fire to clothing, blankets, or upholstery by having the igniter come in contact therewith.

To avoid these difficulties, I have devised 20 a simple and inexpensive construction, which I have illustrated in its preferred form.

Figure 1 is a side view and cross-section of a construction embodying the improvements of my invention.

Fig. 2 is a transverse sectional view taken partly on the plane of the line 2—2 of Fig. 1.

Fig. 3 is a perspective view of the several 30 elements of the construction, the same being shown as separated and arranged in the order in which they are assembled.

In the form shown, 5 is a socket having a shank 6 into which lead the usual cord connectors. 7 is the usual contact by which 35 electrical connection may be established with the translating device, which, in this instance, is an igniter for lighting cigars, etc. The igniter is made removable from the socket 5 and comprises the sleeve 9 surrounding a suitable insulation in which may be mounted the resistance wire 8, which is to constitute the igniting or lighting means. The outer end of the socket 5 is provided with one or more angular slots, for example, 40 ordinary "bayonet slots". Mounted on the side of the igniter sleeve 9 are suitable lugs 11, designed to lock into the angular ends of said slots, for example, as shown in Fig. 1. The shield portion comprises the outer 45 50 55

protector flange 13 and a contracted neck or sleeve 14, which latter is adapted to slide onto the outside of the socket 5. At the inside of said sleeve 14 are one or more lugs 15, which are also adapted to lock into the aforesaid angular slots, the angular ends of said slots being suitable to receive both sets

of lugs 11 and 15. In the preferred form, the construction is such that the lug 15 may be turned into position back of the lug 11. The flange 13 should be suitable to protect 60 the igniter wire 8 against the wind and also against being damaged by being dropped. Again, the cord serves to protect the wire 8 so that the same will not come in contact with the clothing, robes or upholstery and 65 setting fire to or burning the same.

Although the guard is detachable from the socket so that the device can be used without the guard, for instance, for lighting a pipe, it will be obvious that the shape and 70 proportion of the guard with relation to the igniter may permit the device to be used in lighting some pipes without removing the guard.

I claim:

1. An electric cigar lighter comprising a socket having a bayonet slot, an igniter having a pin fitting in said slot and an ash guard having a projection extending into 75 said slot beside said pin.

2. A holder and guard for the purposes described, comprising a socket having an angular slot in its end, a translating device 80 slideable into said socket and having a lug on its side arranged to be locked into said angular slot, and a guard slideable onto said socket and having a lug at its inner side also arranged to be locked into said angular socket.

3. A holder and guard for the purposes 90 described, comprising a socket having an angular slot in its end, a translating device slideable into said socket and having a lug on its side arranged to be locked into said angular slot, and a guard slideable onto said 95 socket and having a lug at its inner side also arranged to be locked into said angular socket, the width of the angular portion of the said slot being sufficient to receive both of said lugs with one behind the other.

4. A holder and guard for the purposes 100 described, comprising a cylindrical socket having one or more angular slots intersecting its outer edge, a contact terminal in said socket, a translating device having a contact terminal at its rear arranged to cooperate with the first mentioned contact terminal, said translating device being surrounded by a sleeve slideably fitting within said socket, said sleeve having a projection arranged to 105 interlock with said angular slot to hold said translating device in operative position with 110

the contacts in engagement, a guard including a flanged guard portion, and a contracted cylindrical portion arranged to slide on the outer side of the aforesaid socket 5 with a lug on the inner side of said contracted portion arranged to interlock in the angular slotted portion of the socket.

5. A holder and guard for the purposes described, comprising a socket having a plurality of angular slots in its end, a translating device slidably fitting within said socket and having a lug arranged to be locked into one of said slots and a guard 10 slidably fitting on the outside of said socket

and having a lug arranged to be locked into one of said slots.

6. In a holder and guard for the purposes described, a socket having an angular slot in its end, a translating device mounted within said socket and exposed at the outer end 20 thereof, a guard mounted on the outside of said socket and projecting beyond the outer end of said translating device to protect the same, said guard having an inwardly projecting lug arranged to be interlocked in 25 said angular slots.

CHARLES F. CUNO.
